(57) **CLAIM**

The ornamental design for a nail gel palette, as shown and described.

DESCRIPTION

FIG. 1 is a perspective view of a nail gel palette showing my new design;

FIG. 2 is a top view thereof;

FIG. 3 is a bottom view thereof;

FIG. 4 is a front view thereof;

FIG. 5 is a rear view thereof;

FIG. 6 is a right side view thereof, a left side view being a mirror image of the right side view; and,

FIG. 7 is a perspective view of the nail gel palette, shown in an open configuration.

The broken lines depict portions of the nail gel palette that form no part of the claimed design.

1 Claim, 7 Drawing Sheets
